UNITED STATES PATENT OFFICE

BENJAMIN B. FRIEND, OF BURBANK, CALIFORNIA

DESIGN FOR A ROCKER CHAIR

Application filed April 13, 1931. Serial No. 39,465. Term of patent 14 years.

To all whom it may concern:

Be it known that I, BENJAMIN B. FRIEND, a citizen of the United States, residing at Burbank, in the county of Los Angeles and the State of California, have invented new, original, and ornamental Design for Rocker Chair, of which the following is a specification, reference being had to the accompanying drawings, forming a part thereof;

Fig. 1 is the perspective view of the rocker chair showing my new design.

Fig. 2 is the side elevation thereof.

I claim:

The ornamental design for a rocker chair, as shown.

BENJAMIN B. FRIEND.
